UNITED STATES PATENT OFFICE

JACK L. SINYKIN, OF ST. PAUL, MINNESOTA

DESIGN FOR A WINDOW DISPLAY STAND

Application filed June 19, 1931. Serial No. 40,271. Term of patent 7 years.

To all whom it may concern:

Be it known that I, JACK L. SINYKIN, a citizen of the United States of America, residing in the city of St. Paul, county of Ramsey, and State of Minnesota, have invented a new, original, and ornamental Design for a Window Display Stand, of which the following is a specification, reference being made to the accompanying drawing, forming a part thereof.

The drawing shows a perspective view of a stand for a window display.

I claim:

The ornamental design for a window display stand substantially as shown.

JACK L. SINYKIN.
